UNITED STATES PATENT OFFICE.

ERNEST CANTELO WHITE, OF NEW YORK, N. Y., ASSIGNOR TO ELECTRIC OUTLET COMPANY, INC., OF NEW YORK, N. Y., A CORPORATION OF NEW YORK.

ELECTRICAL CONNECTING AND SUPPORTING DEVICE.

Application filed April 28, 1923. Serial No. 635,209.

In a copending application filed by the present applicant Ser. No. 635,208, filed April 28, 1923 there is shown, described and claimed broadly an improved mounting for electrical connecting and supporting devices embodying a principle which is susceptible of incorporation in such devices when used either in a wall or in a ceiling. In said application a wall embodiment is illustrated 10 although the claim is of sufficient breadth to cover the construction shown in the present case wherein ceiling devices are illustrated. By the present application it is sought to cover such features of a construction embodying the principles which are peculiarly 15 advantageous in connection with ceiling devices.

The principal object of the present invention is to incorporate in electrical connecting 20 and supporting devices for the ceiling a combination of elements wherein the plug member co-operates with the supporting member in such manner that the two are locked automatically against accidental dislodgment by 25 gravity. A further object of the invention is to incorporate in such devices, wherein such a gravity locking engagement is effected, interengaging parts which are brought home by rotating the plug member with respect to the supporting element. In the 30 specific adaptation illustrated it is proposed that the supporting element shall be formed with a generally triangular recess into which may be introduced a complementary plug member having flanges adapted to enter peripheral slots in the walls of the recess when the plug member is rotated. The gravity lock includes abutments in said peripheral slots which said flanges engage when fully 35 home to prevent reverse rotation of the plug member until and unless the flanges are lifted against the action of gravity out of engagement with said abutments.

In the present construction, the recessed 40 construction in the supporting plate offers the advantages enumerated with respect thereto in the said co-pending application and, in the preferred form, the walls of the recess are formed integral with the supporting plate and this supporting plate carries, in addition, the receptacle into which the terminals of the plug are introduced when the parts are brought into operative engagement.

50 The particular features of the construction

with which the present application is concerned will appear at greater length in connection with the description of the illustrated embodiment shown in the drawings, wherein:

Figure 1 is a view in side elevation of an improved plug member engaged with the supporting element affixed to a ceiling, part of the ceiling being indicated in section.

Figure 2 is a view in plan of the supporting plate and receptacle shown in Figure 1 looking on their reverse side.

Figure 3 is a view in section of the parts shown in Figure 1, the receptacle being shown in side elevation, and taken on the plane indicated by the line 3-3 of Figures 2 and 4 and looking in the direction of the arrows.

Figure 4 is a view similar generally to Figure 2 but taken in section on the plane indicated by the line 4-4 of Figure 3 and looking in the direction of the arrows.

The improved supporting plate *a* is formed with a central recess therein of generally triangular outline as illustrated in said co-pending application Ser. No. 635,208, filed April 28, 1923, the peripheral walls *a'* of this recess being adapted to receive the plug element as will appear hereinafter and being provided with slots *a*² for co-operation with the plug element in a manner to be described. The plate *a* may be secured to the material *b* of the ceiling by screws *c* and may also carry the receptacle *d* as by screws *e* passing through the plate and through a back clamp *d'* carried with the receptacle in a manner which will be evident. A finishing plate *f* of ornamental appearance may be secured to the supporting plate *a* as by screws *f'* in accordance with accepted practice. The plug member is preferably formed in two parts including an ornamental shell or carrier *g* in which is supported the plug proper *h* of insulating material. Terminals *h'* are carried with the plug proper and are adapted to enter the female slots in the receptacle *d* in accordance with common practice. Rotation of the shell *g* with respect to the plug body *h* is permitted in any suitable way as through the engagement of a pin *g'* in the shell with a peripheral groove *h*² in the plug *h*. As shown most clearly in Figure 4 the shell *g* is provided with a plurality of radial flanges *g*² which in the preferred form are disposed equidistant apart so as to

assume a generally triangular relationship for co-operation with the generally triangular recess formed in the plate a .

Since the broadest aspect of the present invention is concerned with the provision of a gravity lock by which the plug member is kept by its own weight and the weight of the appliance attached thereto in predetermined relation to the supporting element it will be understood that the particular devices by which the plug member is engaged with the supporting element may be changed without departing from the spirit of the invention. That is to say, in so far as this phase is concerned the supporting plate a might be of different design but adapted to receive elements on the plug member which are equivalent to the flanges g^2 for supporting engagement and a gravity locking relation be insured without providing the triangular recess in the plate hereinbefore referred to. By way of illustration, the gravity lock may be explained with reference to the drawings. The slots a^2 in the peripheral walls a' of the opening in the plate a are shouldered as at a^3 , adjacent one end to provide abutments for co-operation with the flanges g^2 of the plug carrier g after the flanges have been moved along the slots a^2 until they clear the abutments a^3 and drop in back of them. In use, for instance, the generally triangular plug element is introduced into the complementary recess and the plug revolved to carry the flanges g^2 into the respective slots a^2 . After the flanges have passed the respective abutments a^3 in the slots the plug is permitted to drop by gravity so that the flanges rest against the abutments a^3 and are held against reverse rotation thereby. In order to overcome the action of gravity in insuring this locking relationship it is necessary to raise the plug element bodily against the pull of gravity until the flanges g^2 are above the respective abutments a^3 when the plug may be revolved con-

trariwise to withdraw the flanges from the slots and permit the plug to be withdrawn from the recess. A positive retaining element to prevent this disengagement of the plug with the supporting element may, for safety's sake, be provided in the form of an annular nut i which may be threaded onto the outer side of the circular plug carrier g after the parts have been brought in such relationship as to bring about the gravity locking engagement.

The recess formed in the plate makes the slots in its peripheral walls invisible at ordinary angles of view. When the plug is not in use the resulting installation is neat. When the plug is introduced into the recess and turned home for locking engagement with the supporting element the parts are in compact relationship, the plug being partly housed within the recess.

Changes in details of construction, especially as indicated herein, may be made without departing from the spirit of the invention provided the results are secured.

What I claim is:

In an electrical receptacle, a ceiling plate, a flange formed by a turned in portion of the plate and providing a recess resembling a polygon, openings in the flange in back of the ceiling plate, a plug adapted to be inserted in the recess, a shell over the plug, means to secure the two while permitting relative rotative movement between the two, a polygonal flange on the shell adapted to fit into the recess and engaging the openings upon turning of the shell after insertion into the recess, and shoulders on the lower edges of the openings over which the flanges ride, whereby the gravitational force on the shell prevents backward movement thereof without lifting.

This specification signed this 26th day of February, A. D. 1923.

ERNEST CANTELO WHITE.
